UNITED STATES PATENT OFFICE

AUGUSTE L. SALTZMAN, OF ORANGE, NEW JERSEY, ASSIGNOR, BY MESNE ASSIGNMENTS, TO GENERAL CABLE CORPORATION, OF NEW YORK, N. Y., A CORPORATION OF NEW JERSEY

CHUCK

Application filed August 8, 1930. Serial No. 474,009.

This invention relates to chucks and more particularly to chucks for use on coil winding machines for holding and rotating the coil being wound.

5 An object of this invention is to provide a chuck of the type set forth constructed and arranged to permit ready removal of a finished coil therefrom.

10 A further object is to provide an improved construction of coil holding chuck which can be readily collapsed to release a finished coil or expanded to operative position without requiring the use of any tools.

15 These and other objects which will be apparent to those skilled in this particular art are accomplished by means of the invention illustrated in the accompanying drawings in which—

Fig. 1 is a view in elevation of a coil winding chuck constructed in accordance with one embodiment of this invention.

Fig. 2 is a similar view taken from the end of the chuck illustrated in Fig. 1.

Fig. 3 is a vertical sectional view on the line 3—3 of Fig. 2.

Fig. 4 is a transverse horizontal section on the line 4—4 of Fig. 2.

Fig. 5 is a view similar to Fig. 1 showing the chuck in collapsed position.

30 Figs. 6 and 7 are transverse sectional views on the lines 6—6 and 7—7, respectively, of Fig. 3.

Figs. 8 and 9 are transverse sectional views on the lines 8—8 and 9—9, respectively, of Fig. 4.

Fig. 10 is a partial top plan view with certain parts broken away.

Fig. 11 is a transverse sectional view on the line 11—11 of Fig. 3, and

40 Fig. 12 is a transverse section on the line 12—12 of Fig. 4.

The particular embodiment of this invention which has been chosen for the purposes of illustration comprises a collapsible type of coil supporting chuck which can be readily collapsed to free a finished coil therefrom, or expanded to operative coil winding position without requiring the use of any extraneous tools. The arrangement is such that a single operating lever is employed for placing the

chuck parts either in operative coil supporting position or in inoperative collapsed position. The chuck includes a pair of face plates, one of which is readily removable to permit removal of the finished coil. A locking means for the removable face plate is so arranged that the single operating lever operates the lock for securing the face plate in position when the chuck is expanded or for unlocking the face plate to permit its removal when the chuck is collapsed.

As illustrated, the invention is shown in connection with a coil winding machine 15 having a chuck supporting, rotary, coil winding spindle 16 formed with a projecting threaded end 17 upon which is mounted a sleeve 18. A chuck supporting stud shaft 19 has its inner end secured within and supported by the sleeve 18.

55 A coil supporting core 20, see Figs. 3, 4 and 7, is illustrated as being rectangular in shape, but it will be apparent that any desired configuration of core can be employed, depending upon the form of coil being wound. As illustrated, the core includes an expander 21 slidably mounted on the stud shaft 19 and having inclined upper and lower faces 22 and 23, respectively. Expansible coil supporting upper and lower core blocks 24 and 25, respectively, see Figs. 3 and 7, are slidably mounted on the inclined faces, by suitable dove tail joints, so as to be contracted and expanded by movement of the core member 21 longitudinally of the supporting shaft 19.

60 An inner face plate 26 has a hub 27 slidably mounted upon the movable core member 21 and having an outwardly extending annular portion 28 forming the inner face plate 26 of the chuck. The hub 27 is connected by toggle links 29 with the sleeve 18. A chuck operating collar 30 is slidably mounted on the sleeve 18 and movable longitudinally thereof by a collar operating handle 31 pivoted to a handle supporting bracket 32 mounted on the machine. The handle is provided with collar engaging rollers 33 secured to the handle and positioned within an annular slot 34 formed on the outer surface of the collar to permit the same to be moved longitudinally of the sleeve 18 by the handle 31. The chuck oper-

55

60

65

95

100

100

ating sleeve is provided with diametrically opposed slots 35 in which are positioned the outwardly curved ends 36 of the associated toggle lever 37, and toggle locking screws 38 extend through the collar for locking the toggle against movement when the chuck is in operative position. It will be apparent that in operative position, as illustrated in Fig. 4, the enlarged inner end of the toggle locking screws 38 hold the toggles 29 so as to prevent any movement of the face plate 26, but that inward movement of the chuck operating collar 30 causes the ends of the slots 35 to strike the curved ends 36 of the toggle operating levers 37 and at the same time shift the toggle locking screws 38 so as to permit the toggles to break and move the face plate 26 sufficiently to free it from the pressure of a finished coil.

20 The longitudinally movable core member 21 is also connected to the chuck operating collar 30 by means of pins 39 which extend outwardly through the slots 40 formed in the hub 27, see Figs. 3 and 6, and are connected 25 by links 41 to the adjacent end of the collar 30.

30 The outer face plate 42 of the chuck is formed by a block 43 having an eccentrically positioned rectangular shaft receiving opening 44, see Fig. 3, which permits the block to be placed on the shaft 19 and removed therefrom in a manner somewhat similar to the well-known bayonet lock. The outer end of the slidable core member 21 is provided with a locking pin 45 which engages a pin 35 receiving opening 46 in the block 43 when the chuck members are in expanded, operative position; thus locking the block 43 in position on the shaft between the core blocks 24 and an outer nut 47 which is pinned to the shaft 40 by a pin 48, see Figs. 1 and 5. As shown in Fig. 2, the nut 47 is of rectangular outline corresponding to the opening 44 in the block 43, and it will be apparent that when the chuck is collapsed and the pin 45 withdrawn 45 from the block 43, the latter can be raised until the opening 44 is in line with the nut 47 when the entire block or face plate can be removed from the spindle.

50 As shown in Fig. 7, the core members 24 are provided with threaded wire directing and coil supporting corner pieces 49. The sleeve 30 is provided with a handwheel 50 to permit manual rotation of the chuck in starting the first layer of the coil.

55 In operation, assuming that the parts are in the expanded coil supporting position illustrated in Figs. 3 and 4, a coil will be wound around the core between face plates 26 and 42 in the usual manner. When the coil is completed the strands are quite tightly wound around the core and bear against the opposite face plates with more or less pressure. Merely by shifting the single operating handle 31 to the left to substantially the position indicated in Fig. 5 causes the slidable core mem-

ber 21 to move longitudinally of the core members 24 and 25, collapsing the core by drawing the members inwardly toward the shaft 19 and freeing the coil from the core. As the collar 30 approaches the end of its movement, the ends of the slots 35 engage the curved ends 36 of toggle levers 37 to break the toggles 29 and shift the face plate 26 a distance sufficient to free the strands of the coil from the pressure thereof. Simultaneously, 75 the locking pin 45 is retracted from the face block 43 so that the latter can be lifted off in the manner above described and the finished coil removed from the chuck. To place the parts in their operating position again, the face block 43 is replaced, after which the handle 31 is moved so as to return the parts to their expanded operative position in which the core member 21 is shifted so as to move the parts 24 and 25 to their expanded position and to position the locking pin 45 in the locking slot 46 of the face plate. At the same time, the inner ends of the toggle locking screws 38 have been moved so as to lock the toggles 29 in operative position.

90 The face plates are provided with suitable slots 51 which may be employed to hold cords or tapes for binding the completed coil before releasing, in order to avoid collapse, and also to receive the projecting inner end of the winding wire. This latter serves to lock the wire at the start of the winding operation and leaves the extending lead for subsequent connections.

95 It will be apparent that the chuck is readily collapsible to permit removal of the finished coil and is as readily expandable to operative coil winding position without the use of extraneous tools of any sort.

100 Although I have described a specific embodiment of this invention in more or less detail, it will be apparent that various changes, additions, omissions and substitutions can be made therein without departing from the spirit of this invention or the scope 105 of the appended claims.

110 What I claim as new and desire to secure by Letters Patent is:

115 1. The combination in a coil winding chuck of a rotary spindle, a collapsible core supported by said spindle, relatively movable face plates between which a coil is wound associated with said core and mechanism for simultaneously collapsing said core and separating said face plates to free a finished coil 120 therefrom.

125 2. The combination in a coil winding chuck of a rotary spindle, a collapsible core supported by said spindle and adapted to be expanded or contracted into operative or inoperative position, relatively movable face plates between which a coil is wound associated with said core and a single operating mechanism for simultaneously moving said core and said face plates to operative or inoperative position.

3. The combination in a coil winding chuck of a collapsible core for supporting a coil being wound, relatively movable face plates associated with said core, a slidable support arranged to expand and contract said core, a collar connected to said support, means connecting said collar to one of said face plates and means for moving said collar so as to position said plates and core in either operative or inoperative position.

4. The combination in a coil winding chuck of a rotary spindle, wire supporting and guiding means mounted on said spindle and including a collapsible core having a longitudinally movable sleeve for expanding or contracting said core, relatively movable face plates associated with said core, a collar slidably supported upon said spindle and connected to said sleeve, means connecting said collar to one of said face plates so as to simultaneously move said face plate and said core to operative or inoperative position and means operated by said collar for locking the other of said face plates in position.

25 5. The combination in a coil winding chuck of a rotary spindle, a core for supporting the coil being wound, a pair of face plates associated with said core and between which the coil is wound, one of said face plates being removable to permit removal of the finished coil from said core and means for releasing the pressure of the finished coil from said removable face plate prior to removal thereof from said spindle.

35 6. The combination in a coil winding chuck of a rotary spindle, a core for supporting the coil being wound, a pair of face plates associated with said core and between which the coil is wound, one of said face plates being removable to permit removal of the finished coil from said core, means for locking said removable face plate in position, means for freeing said removable face plate from the pressure of a finished coil and means operated thereby for unlocking said removable face plate to permit removal thereof from the machine.

7. The combination in a coil winding chuck of a collapsible core for supporting the coil being wound, a removable face plate co-operating with said core, means for locking said face plate in position and means for simultaneously collapsing said core and unlocking said face plate to permit removal thereof from said machine.

8. The combination in a coil-winding chuck of relatively movable face plates between which a coil is wound, one of said face plates being removable to permit removal of the finished coil, means for locking said face plate against removal, and means for simultaneously separating said face plates and unlocking said removable face plate.

9. The combination in a coil-winding chuck of a supporting member, a face plate adapted

to be mounted thereon, a locking device for preventing removal of said face plate, and means forming a unitary part of said chuck mechanism for rendering said locking device ineffective.

10. The combination in a coil-winding chuck of a rotary core for supporting the coil being wound, a supporting member, a face plate adapted to be mounted on said supporting member and having an opening permitting removal of said face plate after said plate has been shifted laterally of said member, and means for normally locking said face plate against lateral movement.

11. The combination in a coil-winding chuck of a supporting member, a pair of relatively movable face plates between which a coil is wound, one of said face plates being removable from said support, a slideable member provided with means for locking said removable face plate in operative position, and means for sliding said member so as to unlock said face plate.

In testimony whereof, I have signed my name to this specification this fourth day of August, 1930.

AUGUSTE L. SALTZMAN.
